[57] CLAIM

The ornamental design for a toy toucan bird figure, as shown and described.

DESCRIPTION

FIG. 1 is a side view of a toy toucan bird figure showing my new design, and shown with the mouth open, the unshown opposite side being of identical appearance; FIG. 2 is a front view thereof, with mouth closed; FIG. 3 is a rear view thereof; FIG. 4 is a bottom view thereof; and FIG. 5 is a perspective view thereof.

FIG.5
